SUSPENSION RAILWAY

Walter C. Cox, Denver, Colo.

Application February 6, 1946, Serial No. 645,827

3 Claims. (Cl. 105—155)

1

This invention relates to improvements in suspension railways and has for its object the production of a novel railway track and means for suspending a car therefrom.

There are many places where railways are required where the business does not justify the expense of building a regular railway and it is the object of this invention to produce a simple construction of railway that can be readily be built in any place, regardless of the contour of the land, at a comparatively low cost.

The ordinary railway construction requires the rails to be laid on a solid road bed and limited quite strictly as to inclination or grade, and such construction requires much grading and other expensive operations.

The railway that forms the subject matter of this application does not require the ground to be graded and therefore removes one of the largest items of expense in connection with railway construction.

This invention, briefly described, consists in providing a number of inverted U-shaped supports that have their lower ends embedded in the ground, preferably in concrete blocks, and whose upper or curved ends are cut, forming a central opening. Rails are positioned on opposite sides of the opening and a railway car suspended from them.

The whole weight of the car is supported by the wheels that rest on the rails and therefore a high friction is obtained that makes it possible for the car to travel over grades that would be prohibitive for a railway of ordinary construction.

Having thus stated the objects of the invention and, in a general way, its construction, the railway will now be described in greater detail and for this purpose reference will be had to the accompanying drawing in which the invention has been illustrated, and in which:

Figure 1 is a side elevation showing a short section of the railway track with a car in position thereon;

Figure 2 is a front end elevation taken looking through plane 2—2, Figure 1;

Figure 3 is a section taken on line 3—3, Figure 2, showing the parts to an enlarged scale; and

Figure 4 is a section taken on line 4—4, Figure 3.

In the drawing reference numeral 10 designates the surface of the ground and reference numeral 11 the U-shaped supports, while reference numeral 12 designates the rails.

2

The supports are formed in the shape of an ordinary wire staple or an inverted U. The side members 13 extend into the surface of the ground and are preferably embedded in concrete blocks 14. The upper ends of the supports are curved inwardly on the arc of a circle as indicated at 15. Transverse frame members 16 are provided, and, in addition thereto, diagonal braces 17 may be provided to hold the support from moving laterally during operation.

It will be observed from Figure 4 that the supports are separated at the top as indicated by reference numeral 18 and secured to each of the adjacent ends are rails 12. The rails may be of any suitable construction, but have been shown as formed somewhat like ordinary railway rails.

The car, which has been designated by reference numeral 19 in Figure 1, is provided with a floor 20, vertical side walls 21 and an arched roof 22, which is curved about the same center as parts 15 of the supports. The car may be provided with passenger seats 23 and suitable windows, if it is to be used for passenger travel. If the railway is to be used more particularly for freight, suitable modifications of the car are made. Resting on the rails 12 in spaced relation, are two two-wheel trucks, each truck comprising two wheels that have been designated by reference numeral 24 and which have inner and outer flanges 25. The wheels are connected by an axle 26 that carries a sprocket wheel 27. The car is provided at a point above its center of gravity with a transversely extending shaft 28 that is journaled in bearings 29. Shaft 28 carries a sprocket wheel 30. A sprocket chain 31 encircles sprocket wheels 27 and 30 and serves both to support the weight of the car and to transmit power to wheels 24. As shown in Figure 1, there are two supporting trucks. Positioned within the chamber 32 is an engine 32a of any suitable type, such as a Diesel or ordinary internal combustion engine or an electric motor. This is connected with shaft 28 and rotates the same. When shaft 28 rotates, it turns wheels 24 on their axles and, since these rest on the top rails 12, the car will move along the rails. As a safety feature, two steel links 33 interconnect shafts 26 and 28. The weight of the car is supported by the sprocket chains 31 during operation and links 34 do not ordinarily support any load. However, if the sprocket chain should break, the weight of the car will then be supported by the links which will prevent the end of the car from dropping down, if a break occurs. The links are provided with oblong open-

ings 35 for the reception of shaft 28 so as to reduce to a minimum any friction that might be present.

Since the car is suspended from the two trucks by the sprocket chains, or belts, which may be substituted for the chains, a line joining the axis of shafts 26 and 28 will be vertical when the parts are stationary, regardless of the inclination of the track. When the car is in motion, the trucks will move forwardly away from the vertical a sufficient distance to produce the necessary component for moving the car body.

The sides of the car are provided with concave rails 36 and rubber tired wheels 37 may be mounted for rotation on the supporting frame. In case the car should move outwardly, due to centrifugal force, or otherwise, the rails 36 will contact with the wheels 37 and limit such outward movement to a predetermined amount and prevent the car from hitting the vertical supports.

If an internal combustion engine like a gasoline engine is used, the power unit can be contained entirely in the compartment 32. If an electric motor is used, suitable means comprising a trolley must be provided to transmit current to the motor.

Although the invention has been illustrated and used in connection with a passenger car, it is to be understood that the car may be used for transportation of freight entirely and that its shape may be varied so as to obtain the best results.

As this train is intended for high speed travel, the car is preferably streamlined, but it may be of any shape desired.

The railway is especially well adapted for use in mountainous regions for example, in a mining region, for carrying ore and other equipment. The car body may be of any length or size desired. The windows which have been illustrated in the drawing and designated by reference numeral 38 may be omitted.

The trucks are preferably interconnected by a rigid bar 39 that serves to keep them in predetermined spaced relation.

Attention is also directed to the fact that although the railway is suitable for transporting passengers and freight, it is also of a construction that can be used where small quantities of material are to be transported and the size can therefore be greatly varied.

The trucks have been shown and described as having two wheels each. It is to be understood that each truck may have two pairs of wheels where this is found to be desirable.

Power may be transmitted to one truck only, or to both as may be desired. The endless power transmission element 31 has been shown and described as a sprocket chain. It is to be understood, however, that any other equivalent power transmission element may be substituted, such, for example, as one or more V-type belts or flat belts, etc. Where sprocket wheels and sprocket chains are mentioned, these terms are to be construed to include mechanical equivalents.

From Figure 4 it will be observed that each wheel 24 has two flanges, one engaging the inside and the other the outside of the corresponding rail. Flanges 25 keep the rails in properly spaced relation at all times and prevent them from approaching each other or spreading.

If it is found necessary or desirable, the ends of the supports may be interconnected by a yoke 40

like that shown in Figure 2. The wheels may have rubber tires 41, or the rails may have a rubber strip vulcanized to their upper surfaces as indicated by numeral 42 in Figure 4. The rubber tires and/or the rubber surfaced rails deaden sounds and make the railway practically noiseless.

Having described the invention what is claimed as new is:

1. A suspension railway comprising, a plurality of inverted U-shaped supports, the lower ends of the legs thereof being secured to a railway bed and the arch of the U being arcuate and severed at the center thereof to form an opening, railway rails secured to the supports on each side of the openings therein, a truck having at least one pair of double flanged wheels mounted on the rails, a car body positioned between the supports and underneath the arch, a shaft positioned in the car and mounted to rotate about an axis extending transversely thereof, means comprising a motor carried by the car, for rotating the shaft, means for transmitting rotary motion from the shaft to the wheels and for supporting the car from the truck, comprising an endless power transmission element encircling the shaft and the axis of one pair of truck wheels, and safety links connecting the car with the truck to support the weight of the car in case the power transmission element should break.

2. A suspension railway in accordance with claim 1 wherein each leg of the U-shaped supports rotatably carries a wheel, and the car body is provided with rails adapted to engage with the wheels upon excessive lateral movement thereof.

3. A suspension railway comprising a plurality of inverted U-shaped supports, the lower ends of the legs thereof being secured to a railway bed and the arch of the U being arcuate and severed at the center thereof to form an opening, railway rails secured to the supports on each side of the opening therein, two trucks mounted on the rails, means interconnecting the trucks to hold them in spaced relation, each truck having at least one pair of double flanged wheels, the flanges serving to hold the rails from relative transverse movement, a sprocket wheel or the like, positioned between the wheels, an elongated car positioned in the space between the vertical sides of the supports, beneath the arches thereof, two shafts extending transversely of the car, spaced the same distance as the trucks, at least one of the shafts having a sprocket wheel and an endless sprocket chain encircling the sprocket wheel on the shaft and the sprocket wheel on the corresponding truck, means comprising a motor for rotating the shafts and the wheels on the corresponding truck, and a safety link connecting each truck with the car body to prevent it from dropping if a sprocket chain breaks.
